UNITED STATES PATENT OFFICE.

JOHN V. HECKER, OF NEW YORK, N. Y.

BOLTING-MACHINE FOR FLOUR-MILLS, &c.

SPECIFICATION forming part of Letters Patent No. 318,983, dated June 2, 1885.

Application filed January 23, 1885. (No model.)

To all whom it may concern:

Be it known that I, JOHN V. HECKER, a citizen of the United States, and a resident of the city, county, and State of New York, have 5 invented certain new and useful Improvements in Separators or Sifting Apparatus for Milling Purposes, of which the following is a specification.

My invention relates to improvements in 10 bolting-machines for flour-mills or wherever separating or sifting is desired.

The invention will first be described, and then pointed out in the claim.

In the accompanying drawings, Figure 1 is 15 a plan or horizontal view of the sieve, frame, and moving mechanism. Fig. 2 is a lengthwise vertical section of the same. Fig. 3 is a side elevation of the same. Fig. 4 is an end elevation. Fig. 5 is a transverse section illustrating the manner of supporting the loose sieve by the supporting and vibrating frame.

A represents the sieve placed closely within the frame, so as to be readily removable whenever desired. B represents the frame for supporting the sieve. Sufficient space is left between the sieve and its supporting-frame to allow the sieve free play lengthwise, sidewise, or both, if desired. The sieve may slide upon ways b formed in the frame, as shown in Figs. 20 2 and 5, or any other suitable means for the purpose. C is a box with drawer for receiving material sifted. D are bearings supporting a motion-plate and the shaft therefor; E, bearings supporting main shaft; F, part of frame 25 to which bearings are fastened. G is the main frame of the machine. K is the driving-wheel. M are motion-plates or crank-disks carrying the arms B', forming a part of frame B containing the sieve. O are geared miter-wheels 30 giving motion to the plates M. X is the main

shaft of the machine. As the shaft X is revolved by motion imparted through driving-wheel K the miter-wheels O are revolved, giving motion to the plates or crank-disks M, upon which are pivoted the arms B' of frame B, giving thereto a rotary motion, carrying therewith the frame B and the sieve A, and as the sieve is loosely placed within the frame B it will strike against the sides of the frame, giving sufficient jar to shake down or out of the meshes 45 of its gauze bottom any particles of material likely to lodge within them, so that it becomes impossible for them to become clogged, and thereby inoperative. Any number of these frames with sieves may be arranged in a series—one above another—within a suitable casing. If sieves of considerable length are used, the frame may be braced and strengthened by cross-pieces at intervals or iron rods beneath the sieve, and for very heavy frames 50 rollers may be employed beneath to run upon the ways provided in any suitable manner. The frame in such instances would be moved lengthwise, forward, and backward only, and the end pieces, B, may be hinged or pivoted 55 to the frame to admit of such motion.

What I claim as new, and desire to secure by Letters Patent of the United States, is—

The herein-described sifting-machine comprising the vertical shafts geared to revolve 70 together, the crank-disks M, the frame B, having the arms B', and the sieve A, loosely held in said frame, so as to have motion in all directions, substantially as and for the purposes set forth.

JOHN V. HECKER.
